PORTRABLE CABIN

John H. Ryan, 17 Fernalroy Blvd., Toronto,
Ontario, Canada

Filed Mar. 12, 1962, Ser. No. 69,231

Term of patent 14 years

(Cl. D13—1)

Fig. 3

FIG. 1 is a bottom front perspective view of a portable cabin showing my new design.

FIG. 2 is a side elevation view thereof; and

FIG. 3 is a top plan view thereof.

The undisclosed side is substantially the same in appearance as the side shown in FIG. 2 and the rear is substantially plain.

I claim:

The ornamental design for a portable cabin, as shown and described.
